ROAD GRADER.

APPLICATION FILED MAY 29, 1908.

900,369.

Patented Oct. 6, 1908.

2 SHEETS—SHEET 2.

UNITED STATES PATENT OFFICE.

ELIJAH A. HOLLENBECK, OF FUNK, NEBRASKA,

, has been granted a patent by the United States Patent Office, for an improvement in road graders, as described in the following specification.

Specification of Letters Patent. Patented Oct. 6, 1908.

Application filed May 29, 1908. Serial No. 435,770.

To all whom it may concern:

Be it known that I, ELIJAH A. HOLLENBECK, a citizen of the United States of America, residing at Funk, in the county of Phelps and State of Nebraska, have invented certain new and useful Improvements in Road Graders, of which the following is a specification.

This invention relates to road graders and it has reference particularly to an excavating and side delivery conveying device, applicable to ordinary traction engines and detachably secured thereto.

An object of the invention is to provide novel means for converting an ordinary traction engine into a road grader and the invention comprises novel details of construction and arrangement of parts to be hereinafter more fully described and claimed. The attachment is designed to prove efficient and satisfactory in use and comparatively inexpensive to produce.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, in which—

Figure 1, illustrates a side elevation of a traction engine with the improvement applied thereto. Fig. 2, illustrates a front view thereof. Fig. 3, is a top plan view of the conveyor.

In these drawings A, indicates a traction engine of any desired type.

B is a draft bar for the excavator, said draft bar comprising two approximately E-shaped members connected by bolts b, but separated from each other to provide a space for the reception of an excavator beam C; said beam having its outer end secured to a bracket c, attached to the draft bar. Undue play or lateral movement of the beam is prevented by reason of the fact that said beam is engaged by the members of the draft bar.

The inner end of the beam is curved under and secured to a mold board D, said mold board having the usual plow point d. The excavating device resembles an ordinary plow-share except that the usual land side is omitted.

A brace E extends rearwardly diagonally

from the mold board and has its end pivotally connected to the plate e, which plate is bolted to the under surface of the boiler of the engine. The draw bar has a chain or other connection F, secured to it and the opposite end of said chain is attached to the front of the engine and it is by said means that the draw bar is caused to travel with the engine, although the brace E also pushes the excavator somewhat. The front end of the draw bar is suspended by the cable G, which runs over a pulley H, on the bracket h, attached to the boiler and said cable extends rearwardly to the drum I, on which it is wound, the said drum being rotated by the crank handles i. The rear end of the draw bar is supported in the rear frame J, of the engine, or it may be secured to any other part of the said engine. Clips K are secured to the front axle of the engine and a rod k is mounted to partially rotate therein. Said rod has a depending arm L, and an arm l, at right angles to said rod k. This arm L, is designed to impinge the road bed or surface being graded and acts as a brace in offsetting the lateral resistance due to the action of the plow or excavator as, it is thought, is obvious. The arm l, has a connection M, with the front end of the boiler which acts as a stay to hold the arm L, against movement in one direction. When the excavating apparatus is not working the arm L may be elevated and supported in any convenient manner.

The excavating device delivers the material to an elevator or carrier extending transversely to the line of action of the excavator, and said carrier has a frame comprising the sections N and O, suitably pivoted together at the points n, o. The frames have rods P, to which the rollers Q, are applied, said rollers being arranged in pairs on said rods. As shown in the drawing, the rollers are oppositely tapered toward their meeting ends and when the endless apron or belt R, is run thereover, its longitudinal center will be lower than its edges, and hence the material will be directed to the center of the carrier. A drum S, is journaled in the outer end of the frame and the apron belt is driven thereby through the medium of the beveled gear wheels T and U. The gear wheel U is rotated by the shaft V, and said shaft is journaled in bearings applied to the sides of the frames. In order to permit the outer conveyor frame to

be adjusted with relation to the inner section of said frame, the shaft is provided with joints, or if preferred, a form of flexible shaft may be employed.

5 The outer section of the conveyer frame is held in adjusted position by flexible connections W , which are attached to the ears w , on the sides of the frame and said connections W , are wound on the drum X , journaled in 10 the ends of the bars Y . The bars are bolted to the engine boiler or other part of the engine and they have braces y , also bolted to the boiler. The lower ends of the bars Y , have longitudinally disposed internal racks 15 y' , in which the pinions y^2 , are adjustable. One of the roller rods projects beyond the side of the frame and the pinions y^2 , are mounted on said extensions and engage the racks y' . A hand wheel y^3 , is applied to rotate the pinions and said pinions are held in adjusted position by a dog y^4 , pivoted to a side of the bar Y , to engage the pinion on the rod. The inner frame section is thus adjusted by the rack and pinion device and the 20 outer frame section is adjusted by means of the drum and flexible connections. The inner end of the conveyer shaft and the sprocket wheel Z , mounted on it and the sprocket chain z , run thereover, are driven 25 by the sprocket wheel z' which is substituted for an ordinary belt wheel on the drive shaft z^2 , of a traction engine. The bracket z^3 , serves as a bearing for the conveyer shaft and said bracket is bolted to and depends from 30 the engine boiler.

35 In order that the conveyer may be moved vertically as the excavating device is adjusted, the brace E , is provided with an eye e^2 , through which a rod E^2 , extends, said rod being connected at the rear to a lever E^3 , by 40 which the rear end of said rod may be adjusted. As the rod E^2 , extends through the eye e^2 , and into the frame of the conveyer, it follows that any vertical movement of the 45 rod E^2 will be communicated to the conveyer, and hence the conveyer will move as the rod E^2 , is moved. A brace E' extends from the draw bar B transversely of the engine and said brace has its opposite end connected to 50 the lower end of the rack bar Y as fully shown in Fig. 2.

I claim:

1. A road grader comprising an excavator, a draw-bar, said excavator having connection with said draw-bar, a conveyer adapted to receive the dirt upturned by said excavator, means of connection between said excavator and the grader frame, having an eye member, a rod member engaging the latter and said conveyer, and means for manually actuating said rod member. 55

2. A road grader comprising an excavator, a draw-bar formed of connected approximately E -shaped members spaced apart to receive between them the beam of said excavator, and having a bracket to which is connected the forward end of said excavator beam, means of connection between said excavator, and the grader frame having an eye member, a conveyer adapted to receive the 60 dirt upturned by said excavator, a rod member extending through said eye member and connecting with said conveyer, and manually actuated means for said rod member. 65

3. A road grader comprising a conveyer or carrier in sections, means for effecting the adjustment of the upper conveyer section and its retention in position and additional adjusting means for the lower conveyer section, an excavator arranged to deliver the 70 upturned earth into said conveyer, and means for effecting the simultaneous adjustment of said conveyer and said excavator for co-operative action as set forth. 75

4. A road grader comprising a draw-bar, 80 means for adjustably suspending the forward end of said draw-bar in position, an excavator carried by said draw-bar, a conveyer for receiving the dirt from said excavator, means of connection between said 85 excavator and the grader frame, a manually actuated rod member and means for adjusting said conveyer and said excavator from and by a common manually actuated means.

In testimony whereof I affix my signature 90 in the presence of two witnesses this 25th day of May, 1908.

ELIJAH A. HOLLENBECK.
